UNITED STATES PATENT OFFICE.

JAMES G. PORTTEUS, OF MARION, INDIANA, ASSIGNOR OF ONE-HALF TO SANFORD CLINTON JONES, OF MARION, INDIANA.

PUZZLE.

Application filed April 27, 1922. Serial No. 556,889.

To all whom it may concern:

Be it known that I, JAMES G. PORTTEUS, a citizen of the United States, residing at Marion, in the county of Grant and State of Indiana, have invented a new and useful 5 Puzzle, of which the following is a specification.

This invention relates to the class of puzzles and magics, the primary object of the 10 invention being to provide a puzzle which will be exceptionally difficult to operate, and one wherein the operator's skill will be tested in the carrying out of the purpose of the invention.

Another object of the invention is to provide a puzzle including a container wherein 15 the walls thereof are relatively straight, thereby eliminating pockets or recesses in which a ball may be held while positioning another ball.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, may be made within 25 the scope of what is claimed, without departing from the spirit of the invention.

Referring to the drawing:—

Figure 1 is a plan view of a puzzle constructed in accordance with the present invention.

Figure 2 is a transverse sectional view 35 through the device.

Referring to the drawing in detail, the reference character 5 designates the base of the body portion of the puzzle which is 40 formed preferably of wood, and to which the side walls 6 of the puzzle are secured as by means of the nails 7. The side walls 6 are formed preferably of sheet metal so that the same will be exceptionally cheap to 45 manufacture, the same being formed by a well known stamping operation.

Formed at the upper edges of the side walls are the inwardly extending flanges 8 to which the transparent cover 9 is secured, 50 it being preferred however to secure the

transparent cover by means of cement or other adhesive material. A pair of spaced walls 10 are positioned in each corner of the body portion of the puzzle, it being understood that the preferred form of the 55 puzzle is rectangular.

The spaced walls 10 provide pockets to receive the movable elements 11, which are in the form of metal balls, the space between the walls 10 of each pocket being of a width 60 greater than the diameter of the balls to permit the balls to move freely within the pockets, the balls being shown in dotted lines as positioned within the pockets. Each of these walls 10 is formed with a downwardly extended portion adapted to lie against the sides of the body portion 5 to secure the walls 10 in position.

To accomplish the purpose of the invention, the person operating the puzzle tilts 70 the body portion in any desired direction to cause the balls to move into the pockets, the point of the game being to move the body portion or puzzle in such a way that a ball will pass into each pocket, and be held 75 therein.

Having thus described the invention, what is claimed as new is:—

In a puzzle, a base, side walls secured to the base and extending upwardly therefrom, 80 said walls having inwardly extended flanges, a cover of translucent material adapted to engage the flanges, a pair of spaced walls arranged in the corners of the base and extending at oblique angles with respect to the side walls, the central portion of the base being free of obstructions, balls mounted on the base to roll thereover, and said balls adapted to move from positions between the obliquely disposed walls at one corner of the 85 base directly across the base to a position between the walls at the opposite corner of the base.

In testimony that I claim the foregoing as my own, I have hereto affixed my signature 90 in the presence of two witnesses.

JAMES G. PORTTEUS.
